CLAIM

The ornamental design for a housing, measuring instrument, and assembly as shown and described.

DESCRIPTION

FIG. 1 is an isometric view of a housing, measuring instrument, and assembly;

FIG. 2 is a rear isometric view of the housing, measuring instrument, and assembly of FIG. 1;

FIG. 3 is a front view of the housing, measuring instrument, and assembly of FIG. 1;

FIG. 4 is a rear view of the housing, measuring instrument, and assembly of FIG. 1;

FIG. 5 is a left side view of the housing, measuring instrument, and assembly of FIG. 1;

FIG. 6 is right side view of the housing, measuring instrument, and assembly of FIG. 1;

FIG. 7 is a top view of the housing, measuring instrument, and assembly of FIG. 1;

FIG. 8 is a bottom view of the housing, measuring instrument, and assembly of FIG. 1;

FIG. 9 is a front perspective exploded view of the top, middle, and bottom parts of the housing, measuring instrument, and assembly of FIG. 1;

FIG. 10 is a rear perspective exploded view of the top, middle, and bottom parts of the housing, measuring instrument, and assembly of FIG. 9;

FIG. 11 is a front exploded view of the top, middle, and bottom parts of the housing, measuring instrument, and assembly of FIG. 9;

FIG. 12 is a rear exploded view of the top, middle, and bottom parts of the housing, measuring instrument, and assembly of FIG. 9;

FIG. 13 is a left side exploded view of the top, middle, and bottom parts of the housing, measuring instrument, and assembly of FIG. 9;

FIG. 14 is a right side exploded view of the top, middle, and bottom parts of the housing, measuring instrument, and assembly of FIG. 9;

FIG. 15 is a top view of the housing, measuring instrument, and assembly of FIG. 9;

(Continued)

FIG. 16 is a bottom view of the housing, measuring instrument, and assembly of FIG. 9;
 FIG. 17 is a front perspective view of the top part of the housing, measuring instrument, and assembly of FIG. 1;
 FIG. 18 is a rear perspective view of the top part of the housing, measuring instrument, and assembly of FIG. 17;
 FIG. 19 is a front view of the top part of the housing, measuring instrument, and assembly of FIG. 17;
 FIG. 20 is a rear view of the top part of the housing, measuring instrument, and assembly of FIG. 17;
 FIG. 21 is a left side view of the top part of the housing, measuring instrument, and assembly of FIG. 17;
 FIG. 22 is a right side view of the top part of the housing, measuring instrument, and assembly of FIG. 17;
 FIG. 23 is a top view of the top part of the housing, measuring instrument, and assembly of FIG. 17;
 FIG. 24 is a bottom view of the top part of the housing, measuring instrument, and assembly of FIG. 17;
 FIG. 25 is a front perspective view of the middle part of the housing, measuring instrument, and assembly of FIG. 1;
 FIG. 26 is a rear perspective view of the middle part of the housing, measuring instrument, and assembly of FIG. 25;
 FIG. 27 is a front view of the middle part of the housing, measuring instrument, and assembly of FIG. 25;
 FIG. 28 is rear view of the middle part of the housing, measuring instrument, and assembly of FIG. 25;
 FIG. 29 is a left side view of the middle part of the housing, measuring instrument, and assembly of FIG. 25;
 FIG. 30 is a right side view of the middle part of the housing, measuring instrument, and assembly of FIG. 25;
 FIG. 31 is a top view of the middle part of the housing, measuring instrument, and assembly of FIG. 25;
 FIG. 32 is a bottom view of the middle part of the housing, measuring instrument, and assembly of FIG. 25;
 FIG. 33 is a front perspective view of the middle part of the housing, measuring instrument, and assembly of FIG. 1;
 FIG. 34 is a rear perspective view of the middle part of the housing, measuring instrument, and assembly of FIG. 33;
 FIG. 35 is a front view of the middle part of the housing, measuring instrument, and assembly of FIG. 33;
 FIG. 36 is rear view of the middle part of the housing, measuring instrument, and assembly of FIG. 33;

FIG. 37 is a left side view of the middle part of the housing, measuring instrument, and assembly of FIG. 33;
 FIG. 38 is a right side view of the middle part of the housing, measuring instrument, and assembly of FIG. 33;
 FIG. 39 is a top view of the middle part of the housing, measuring instrument, and assembly of FIG. 33; and,
 FIG. 40 is a bottom view of the middle part of the housing, measuring instrument, and assembly of FIG. 33.
 The dashed lines illustrate environment that does not form a part of the present invention, and no claim is made to the material illustrated with dashed lines.
